UNITED STATES PATENT OFFICE.

LAFAYETTE J. JACKSON, OF EAST ST. LOUIS, ILLINOIS.

REINFORCED-CONCRETE RAILWAY CROSS-TIE.

961,697.

Specification of Letters Patent. Patented June 14, 1910.

Application filed March 11, 1910. Serial No. 548,689.

To all whom it may concern:

Be it known that I, LAFAYETTE J. JACKSON, a citizen of the United States, residing at East St. Louis, in the State of Illinois, 5 have invented certain new and useful Improvements in Reinforced-Concrete Railway Cross-Ties, of which the following is a specification.

This invention comprehends certain new 10 and useful improvements in reinforced concrete railroad ties and the invention has for its primary object a simple, durable and efficient construction of tie which embodies a novel and useful construction and arrangement 15 of rail supports that are formed by wooden blocks embedded in the concrete tie and preferably resting with their lowermost faces on the reinforcing bar which forms a component part of the body portion of the 20 tie whereby the rails will rest practically on cushions and the liability of the tie being broken by the wearing of the rails will be precluded.

With these and other objects in view as 25 will more fully appear as the description proceeds, the invention consists in certain constructions, arrangements and combinations of the parts that I shall hereinafter fully describe and claim.

30 For a full understanding of the invention, reference is to be had to the following description and accompanying drawings in which:

Figure 1 is a perspective view of a cross tie embodying the improvements of my invention. Fig. 2 is a longitudinal sectional view thereof; Fig. 3 is a top plan view of one of the wooden blocks employed; Fig. 4 is a diagonal sectional view of said block; 40 and, Fig. 5 is a perspective view of a portion of the reinforcing bar.

Corresponding and like parts are referred to in the following description and indicated in all the views of the accompanying drawings by the same reference characters.

My improved cross tie embodies a concrete body portion 1 in which is embedded a reinforcing bar 2 preferably composed of soft steel and preferably located nearer the 50 bottom of the tie than the top, said bar 2 extending substantially throughout the length of the tie but stopping short of the ends thereof, and the ends of the bar being split, the split ends being turned upwardly and 55 downwardly as indicated at 3 to assist in the reinforcing action. Preferably the bar

2 is located at some distance from the side edges of the body portion 1, and is about one-half the width of the body portion, as clearly indicated in Fig. 1.

The body portion 1 of the tie has embedded therein near the ends, wooden blocks 4 that are preferably the same width as the reinforcing bar 2, the said blocks 4 preferably resting directly upon the reinforcing 60 bar, and being secured thereto, each by a countersunk bolt 5, the threaded end of which is located in an opening 6 formed in the body portion 1 below the bar 2, whereby the nut 7 may be easily screwed on the bolt and readily removed, whenever desired, whereby the blocks may be removed when worn and replaced. Preferably the upper edges of the blocks 4 are slightly raised above the upper edge of the body portion 1 70 as clearly illustrated in Fig. 2.

In the preferred method of manufacture, the wooden blocks 4 are first drilled to provide the hole for the bolt 5, said hole being so located that it will lie directly along the 80 rail after the latter has been secured in place, and the blocks are initially formed with preferably round spike holes 8 arranged in offset relation to each other as shown, and designed to receive square 85 spikes which are of somewhat larger diameter so as to produce a rigid fastening. After the blocks have thus been formed, they are soaked in creosote to preserve them.

From the foregoing description in connection with the accompanying drawings, the operation of my improved reinforcing concrete railway tie will be apparent.

In forming the ties, the blocks 4 are drilled to produce the bolt and spike holes 90 and are then soaked in creosote. They are then placed on the reinforcing bar and the concrete body portion 1 is then molded, the bar being embodied therein. The blocks are secured firmly in place by the bolts 5 which 95 extend through the apertures formed in the reinforcing bar, nuts 7 being secured on the bolts in the openings 6, whereby to tightly bind the blocks to the bar. The rails are then set in place and spikes are driven into 100 the holes 8 whereby to securely fasten the rails to the cushioning blocks 5. No especially designed fastening devices are necessary with my construction and arrangement of parts; as the wooden blocks rest directly 105 upon the bar 2 but do not overlie the side edges thereof, it is obvious that the wear of

the rails on the blocks will not injuriously affect the concrete body portion 1, as it would were the blocks to rest on the concrete, or were the rails to rest directly upon 5 the concrete. Obviously the ties can be cheaply manufactured, and the blocks may be easily secured in place and removed when worn or when for any other reason, it is necessary to replace them.

10 Having thus described the invention, what is claimed as new is:

1. The herein described tie comprising a concrete body portion, a reinforcing bar mounted therein, rail supporting blocks embedded in said body portion and resting directly upon the reinforcing bar, the reinforcing bar being of a width equal to the width of the blocks, the body portion being formed below the blocks and underneath 15 the reinforcing bar with bottom openings leading to the lower face of the bar, bolts extending through the respective blocks and through the bar into said bottom openings, 20

and nuts located in said bottom openings and screwing on the bolts whereby to bind 25 the blocks to the bar.

2. A railroad tie, comprising a concrete body portion, a reinforcing bar embedded therein, and extending throughout the length thereof but stopping short of the 30 ends of the concrete body portion, the ends of the bar being split and turned in opposite directions, for the purpose specified, wooden blocks embedded in the concrete body portion, bolts extending through said 35 blocks, and reinforcing bar, the body portion being formed with bottom openings in which the lower ends of the bolts are countersunk, and nuts working on the lower ends of the bolts substantially as described. 40

In testimony whereof I affix my signature in presence of two witnesses.

LAFAYETTE J. JACKSON. [L. s.]
